Inventor:

Henrietta Bradberry
By David Mayle Hall, Attorney.

UNITED STATES PATENT OFFICE

2,320,027

BED RACK

Henrietta Bradberry, Chicago, Ill.

Application November 28, 1941, Serial No. 420,791

5 Claims.

(Cl. 5—321)

This invention relates to bed attachments especially for use in connection with exposing bed clothes to freshening by air after use.

One of the principal objects of my invention is to provide an attachment which can be readily secured to the foot of a bed, and which is provided with collapsible rod supporting means, and pedal means for opening or collapsing the said attachment.

Another object of my invention is to provide pedal locking means which can be operated from the right or left side of a bed.

Another object of my invention is to provide treadle trip means on either side or both sides of a bed, the said trip means being connected so as to operate in unison.

Another object of my invention is to provide an attachment of the aforementioned character which is simple and practical in construction, simple to operate, efficient and useful in its operation, and of such a simple construction as to warrant economical manufacture in quantity production.

Other features and advantages of my invention will become apparent from examination of the accompanying drawings and the ensuing description, wherein like symbols are used to designate like parts, and in which:

Fig. 1 is a plan view of my invention looking in the direction 1—1 of Figure 2.

Fig. 2 is a longitudinal cross-sectional view taken on the line 2—2 of Figure 1.

Fig. 3 is a view looking in the direction 3—3 of Figure 1.

Fig. 4 is a transversal cross-sectional view on the line 4—4 of Figure 3.

Fig. 5 is a longitudinal cross-sectional view on the line 5—5 of Figure 1.

Fig. 6 is a longitudinal cross-sectional view on the line 6—6 of Figure 2.

Fig. 7 is a view looking in the direction 7—7 of Figure 6.

Fig. 8 is an end view looking in the direction 8—8 of Figure 6.

Fig. 9 is a longitudinal cross-sectional view on the line 9—9 of Figure 6.

Referring more particularly to the drawings, in Figures 1, 2, 3, 4, and 5, my attachment is generally comprised of two clamp portions 15 provided with clamping recesses 16 adapted to receive the legs 13 of the foot of a bed generally designated 10. The clamp portions are firmly secured by virtue of wing screws 17. The mattress of the bed is generally designated 11, and the covering sheet 12. There may be one or more

of these sheets depending on how the bed is made up.

The object of my invention is primarily for airing these sheets and bed clothes 12 after the bed has been slept in, so as to freshen the bed clothes and maintain them in as clean a condition as possible for sleeping the ensuing night.

The clamping portions 15 are provided with extensions 18 which terminate in bearing portions adapted to support the collapsible means used in connection with my invention. The extensions 18 are preferably off-set as indicated, and each carries a treadle member 28 having a treadle arm 29 in one integral piece, which is pivoted at the 15 stud generally designated 30 and shown in detail in Figure 5; it being comprised of a round head 24, and a shoulder portion 25 and a reduced threaded portion 26 engaged by the nut 27. The shoulder portion 25 is of a dimension a few thousandths of an inch larger than the combined thicknesses of the elements 29, 31, and extension 18.

The collapsible means is comprised of a treadle member 29, the short arms 31 and the long arms 32, and as can be seen when the treadle 28 is in the position indicated in the full lines of Figure 2, the collapsible means will be expanded to its full height, whereas when the treadle 28 is allowed to drop in the position indicated in dotted lines, 30 the collapsible means will compactly form itself into the structure indicated in dotted lines in Figure 2.

At the intersection point of the arms 32 and 31 forming the composite lazy-tongs structure 35 of the collapsible means, the hanging or support rods 20 are secured by virtue of shoulder screws 21 as shown in detail in Figure 4, the said shoulder screws having a shoulder body 22 and a reduced threaded body 23. The rods 20 being 40 threaded suitably to receive the threaded shank portions 23 of the screws 21. The shoulder portion 22 is preferably longer in dimension than the combined thicknesses of the hub portion of the elements 32 in order to provide a working fit and eliminate friction. The arms 32 and 31 are also swivellably connected by rivet elements 33 thus permitting extensible and retractable operation.

When it is desired to air the clothes of the bed, the device is set up in the expanded position indicated, and the sheets 12 are placed over the various rungs 20 indicated. The treadle is held normally in the upward position indicated by the dotted lines in Figure 2; whence the device is in collapsed form and it takes up as little space as

possible. When it is to be expanded and set for operation, it is held in engagement by the trip means comprised of the elemental structure indicated more clearly in Figures 6, 7, 8 and 9.

Referring to these figures, the bracket portions 18 are interconnected by a webbed portion 19 having an extension 52 provided with a hub 34 for supporting some of the mechanism later to be described. The extensions 18 are provided with bearing portions 49 so as to secure thereto the pivots 48 upon which the trip means is mounted at either side of said extensions. On each side of the extensions 18 a lug 46 is provided in order to receive in abutting relationship the heel 47 of the trip means 45 which are formed approximately in the shape indicated and which operate in unison in the direction indicated by the dotted lines in Figure 6.

The trip means 45 are connected by virtue of an oscillating link means 42 and the connecting rods 36 and 35 which are secured at points 40 and 41 of the link means 42, and are connected at points 43 and 44 on the trip means 45. The oscillating means 42 is pivotally mounted by virtue of shoulder stud means 38 securely fastened by nut 39. The trip means is normally urged in locked position by the spring means 49 secured to the extension means 18 by virtue of screws 50. Thus, it can be seen that when one of the trip means 45 is urged inwardly by the connection afforded thru the oscillating link means 42 the trip means on the opposing side will be caused to operate inwardly and thus disengage the treadle means 28. The trip means 45 is provided with a ribbed structure 51 in order to permit the treadle 28 shown in dotted lines Figure 6 when moved downwardly to provide a cam action to the trip means thus forcing the trip means inwardly and engaging the said treadle means in locking engagement after the treadle has been brought down to the floor surface 14.

It should be noted that my invention is secured to the legs 13 of a bed preferably in a position where the treadle when in locked engagement is a slight distance from the floor surface 14 in order to permit disengagement and engagement, readily, of the treadle means with the said trip means. When the device is in normal position, that is in its collapsed form, and it is desired to extend it for use in supplying the spaced rack portions 20 as shown in full lines in Figure 2, the foot of a person is used in engaging the treadle as shown in the dotted lines Figure 6, and the tip of the toe is slid along and presses the treadle downward which causes the trip means 45 to be swung to the dotted position and then by virtue of action of the springs 49, the trip means is brought back to its normal position so that when the treadle is released it will abut and engage the trip means which by virtue of its heel means 47 will prevent the treadle from going back to normal position. When it is desired to disengage the treadle means so as to set the rack in normal position when no longer in use, the toe of the foot of a person is slid along the ribbed portion 51 thus causing the trip means to work inwardly to the dotted position thus providing an escapement for the treadle 28 in its bottom position, and by gradually lifting the foot, the treadle is brought up past the locking portion of the trip means 45 and allowed to rest in the up or normal position.

The attachment may be quite weighty if made of metal, hence rods 20 may be made of hollow tubing with threaded plugged ends. Even if tubes be used it is believed that in collapsing the rack means it would be advisable to allow the foot to deter the action of gravity thus minimizing possible damage from continued use.

I believe, I have described rather succinctly the nature and operation of my invention, and 10 I reserve the right to any and all modifications to which it is susceptible in accordance with the scope and spirit thereof, as well as within the purview of the accompanying drawings and the foregoing description; my invention to be 15 limited by the appended claims.

Having thus described and revealed my invention what I claim as novel and desire to secure by Letters Patent is:

1. In a device of the character described, in 20 combination with rack means, and dual treadle means, dual trip means adapted to operate in unison pivotably mounted in a manner to effectuate simultaneous operation of both trip means by virtue of motivation of either of said dual trip means, the said dual treadle means adapted to be engaged by the said dual trip means simultaneously maintaining the said rack means in extended position.

2. In a device of the character described, in 30 combination with rack means, and dual treadle means, dual trip means mounted pivotably on support means, oscillating link means mounted on said support means intermediately disposed between said dual trip means, and connecting 35 rod means swivellably connected at one of their ends to the ends, respectively, of said oscillating link means, their other ends swivellably connected to each of said dual trip means, and spring means normally urging said trip means outwardly, the said dual treadle means adapted to be engaged by the said dual trip means simultaneously maintaining the said rack means in extended position.

3. A device of the character described comprising, U shaped bracket support means provided with clamp means adapted to secure the said bracket support means to a bed, extensible and collapsible rack means comprising, a set of lazy-tongs mounted on each of the arms of the said U shaped bracket support means, and rod means interconnecting the said lazy-tongs structure, treadle means pivotally mounted on each of the arms of the said U shaped bracket support means and connected to the said lazy-tongs structure adapted to effect extension and retraction of the said lazy-tongs structure, and trip means mounted articulately on each of the arms of the said U shaped bracket support means adapted to maintain the said rack means in extended position.

4. In combination, a bed, and a bed rack secured thereto comprising, U shaped bracket support means provided with clamp means adapted to secure the said bracket support means to said bed, extensible and collapsible rack means comprising, a set of lazy-tongs mounted on each of the arms of the said U shaped bracket support means, and rod means interconnecting the said lazy-tongs structure, treadle means pivotally mounted on each of the arms of the said U shaped bracket support means and connected to the said lazy-tongs structure adapted to effect extension and retraction of the said lazy-tongs structure, and

trip means mounted articulately on each of the arms of the said U shaped bracket support means adapted to maintain the said rack means in extended position.

5. A device of the character described comprising, U shaped bracket support means provided with clamp means adapted to secure the said bracket support means to a bed, extensible and collapsible rack means comprising, a set of lazy-tongs mounted on each of the arms of the said U shaped bracket support means, and rod means interconnecting the said lazy-tongs structure, treadle means pivotally mounted on each of the arms of the said U shaped bracket support means and connected to the said lazy-tongs structure adapted to effect extension and retraction of the said lazy-tongs structure, dual

trip means mounted articulately on each of the arms of the said U shaped bracket support means adapted to maintain the said rack means in extended position, the said trip means comprising, trip elements mounted pivotably on each of the arms of the said U shaped bracket support means, oscillating link means mounted on said support means intermediately disposed between said dual trip means, connecting rod means swivelably connected at one of their ends to the ends, respectively, of said oscillating link means, their other ends swivelably connected to each of said dual trip means, and spring means normally urging said trip means outwardly.

HENRIETTA BRADBERRY.
